Inventor,

Rolla O. Heikes
By his Attorney B. Pickering

UNITED STATES PATENT OFFICE.

ROLLA O. HEIKES, OF DAYTON, OHIO.

GUN HAND-PROTECTOR.

SPECIFICATION forming part of Letters Patent No. 397,719, dated February 12, 1889.

Application filed September 12, 1888. Serial No. 285,181. (No model.)

To all whom it may concern:

Be it known that I, ROLLA O. HEIKES, a citizen of the United States, residing at Dayton, in the county of Montgomery and State 5 of Ohio, have invented a certain new and useful Improvement in Gun Hand-Protectors; and I do hereby declare that the following is a full, clear, and exact description of the invention, which will enable others skilled in the art 10 to which it appertains to make and use the same, reference being had to the accompanying drawings, and to the letters of reference marked thereon, which form a part of this specification.

15 My invention relates to improvements in a gun hand-protector used to protect the left hand in supporting the barrels of a double-barreled shot-gun during rapid firing to prevent the same from being burned by the great 20 heat so resulting.

My invention is a substitute for a glove which is ordinarily used for the purpose, the object being to thoroughly protect the hand against the heat of the barrels.

25 The object is accomplished by the device illustrated in the accompanying drawings, in which—

Figure 1 is a top view of the hand-protector as attached to the barrels of a shot-gun. Fig.

30 2 is a transverse section of the same. Fig. 3 is a transverse section of the hand-protector.

Like letters designate like parts throughout the several views.

B, Figs. 1 and 2, is a portion of the barrels 35 of a shotgun, the part immediately beyond the stock, and the part that is grasped by the left hand when in the act of firing the same. A

(shown in the several figures) are views of the hand-protector. The same comprises the metallic plate 2, which covers the under surface of the barrels and is curved to embrace the sides 40 of the same. It may be made of spring-brass or any other suitable metal. Both surfaces of the metal are covered with leather, 1, which is used to prevent the heat of the barrels being 45 conveyed to the hand. Any textile fabric which is a good non-conductor of heat may be substituted for the leather covering, and the attachment of such non-conducting material may be made in any convenient manner, 50 as by sewing, pasting, or riveting. The hand-protector is slipped on over the ends of the barrels to a proper position to suit the grasp of the left hand in firing the gun, and is there held by the resiliency of the metal, thus serving 55 to protect the hand during rapid firing.

Having fully described my invention, what I claim, and desire to secure by Letters Patent, is—

A double-barreled-gun hand-protector comprising a spring metal handle lined with a non-conductor of heat, the edges of which bear against the upper surfaces of said barrels, thereby admitting of longitudinal adjustment, substantially as shown and described. 60 65

In testimony that I claim the foregoing as my own I affix my signature in presence of two witnesses.

ROLLA O. HEIKES.

Witnesses:

B. PICKERING,
SUMNER T. SMITH.
